UNITED STATES PATENT OFFICE.

EDWARD A. FIELD AND EDWARD A. FIELD, JR., OF OAK PARK, ILLINOIS.

INTERNAL-COMBUSTION ENGINE.

1,373,876.

Specification of Letters Patent.

Patented Apr. 5, 1921.

Application filed June 21, 1920. Serial No. 390,612.

To all whom it may concern:

Be it known that we, EDWARD A. FIELD and EDWARD A. FIELD, Jr., citizens of the United States, residing at Oak Park, county 5 of Cook, State of Illinois, have invented certain new and useful Improvements in Internal-Combustion Engines, of which the following is a specification.

This invention relates to improvements in 10 internal combustion engines.

The main objects of this invention are:

First, to provide an internal combustion engine of medium compression which is of high efficiency.

Second, to provide in an internal combustion engine an improved charging or fuel feeding means.

Third, to provide an improved internal combustion engine adapted for the use of 20 the heavier hydrocarbons as fuel in which the fuel is effectively broken up and vaporized when injected into the combustion chamber.

Fourth, to provide an improved internal 25 combustion engine in which the charge is introduced on the compression stroke of the engine.

Further objects, and objects relating to 30 structural details will definitely appear from the detailed description to follow.

We accomplish the objects of our invention by the devices and means described in the following specification. The invention is clearly defined and pointed out in the 35 claims.

A structure which is a preferred embodiment of our invention is clearly illustrated in the accompanying drawing forming a part of this specification, in which:

40 Figure I is a detail longitudinal central section of a structure embodying the features of our invention on a line corresponding to line 1—1 of Fig. II and III.

Fig. II is a detail longitudinal section on 45 a line corresponding to line 2—2 of Figs. I and III.

Fig. III is a detail section on a line corresponding to line 3—3 of Figs. I and II.

Fig. IV is an enlarged detail section on a 50 line corresponding to line 4—4 of Fig. V showing details of the charging means.

Fig. V is an inverted detail view of the parts shown in Fig. IV.

Fig. VI is a detail view partially in section showing a modified form of charging 55 valve.

In the drawing similar reference characters refer to similar parts throughout the several views, and the sectional views are taken looking in the direction of the little 60 arrows at the ends of the section lines.

Referring to the drawing, 1 represents a cylinder and 2 the piston of an internal combustion engine. These parts are shown conventionally. The cylinder is provided with 65 an air inlet valve 3 and an exhaust valve 4. The means for controlling these air inlet and exhaust valves 3 and 4 are not illustrated, as the details of such means form no part of this invention. Means such as cam 70 movements for this purpose are well known in the art.

In the head 5 of the cylinder is a bore 6 having a cylindrical charging chamber member 7 therein communicating with the 75 combustion chamber 8 of the cylinder through a series of spirally disposed ports 9. A plug-like body 10 is threaded into the lower end of this charging chamber member 7 and shouldered to engage the end of the bore, as shown in the drawings. A nut 11 is threaded upon the projecting upper end of the member 7 to retain the parts in position.

The body 10 is provided with a fuel supply passage 12 terminating in an annular passage 13 surrounding the nozzle opening 14 in the nozzle member 15 seated on the body 10. A plunger-like member 16 is arranged in the upper end of the cylindrical 90 member 7 for adjustment therein as by means of a governor whereby the capacity of the charging chamber 17 may be varied.

The cylinder is connected with this charging chamber 17 through the passage 18 having a delivery opening 19 alined with the nozzle opening 14. The passage 18 is provided with a check valve 20.

The delivery ports 9 of the charging chamber are controlled by the sleeve valve 100 21 arranged within the cylindrical charging chamber member 7 and subject to the pres-

sures within the cylinder so that on the compression stroke of the piston, the valve 21 is closed and a blast of air is delivered through the passage 18, the nozzle orifice 19 thereof and through the nozzle opening 14 atomizing a charge of fuel and delivering the atomized fuel into the charging chamber 17.

An auxiliary air inlet 22 is provided for 10 the charging chamber, the auxiliary air inlet being provided with a check valve 24— see Fig. IV.

On the suction stroke of the piston, a 15 vacuum is created and owing to the communication of the charging chamber and the cylinder, a quantity of fresh air or atmospheric air is drawn into the charging chamber and on the compression stroke, as stated, a blast of air is forced into the charging 20 chamber through the passage 18 and carries with it a charge of fuel.

The charging chamber is provided with 25 igniting means consisting in the structure illustrated of the hot bulb 25 disposed oppositely to the nozzle opening 14 so that a charge is ignited in the charging chamber and the combustion produces a pressure within the charging chamber higher than the compression in the cylinder, and the 30 valve 21 is opened and the vaporized but unconsumed fuel in the charging chamber is ejected or escapes through the ports 9 into the combustion chamber or cylinder where it burns when it comes in contact 35 with the air therein.

At the end of the work stroke of the piston, the exhaust valve 4 opens and the burned gases are forced out on the exhaust stroke of the piston.

40 The capacity of the charging chamber 17 is varied by adjusting the plunger-like adjusting member 16 which is preferably controlled by a governor mechanism not shown. By increasing or decreasing the capacity of 45 the charging chamber more or less air will enter and consequently more or less fuel will be delivered.

To control the rapidity with which the fuel and gas is delivered from the charging 50 chamber and thereby securing a timing, we provide an adjustable stop 26 for the valve 21. By adjusting this stop the number of holes 9 uncovered is regulated and thereby the discharge.

55 With this arrangement the amount of fuel for each charge or cycle is quite accurately regulated and by varying the discharge the explosions may be timed thus allowing speed variations without pre-ignition as in running slowly.

As an aid to starting, the member 16 is provided with a passage 27 through which the hot bulb may be heated as by means of a blow torch. As another aid to starting, 60 we provide the fuel passage 12 with a drain

cock 28 so that the heavier fuel may be drawn off and a lighter fuel admitted through the connection 29.

The supply tank for the connection 29 is not illustrated but a suitable arrangement 70 will be readily understood. The main fuel connection 30 and also the supply pipe 29 are provided with check valves 31.

In the modification shown in Fig. VI, a mechanically operated valve 32 is substituted for the valve 21, valve 32 being held normally open by the spring 33 and actuated by the pin 34 and the actuating lever 35 to close the ports 9 on the charging stroke of the plunger. An adjustable stop 36 limits the opening of the valve 32 and thereby secures the timing, as has been described for the embodiment previously described. Where a mechanically operated valve is provided it is arranged on the outside of the member 16. The embodiment shown in Fig. VI secures a positive action of the valve and its movement may be accurately timed.

With this arrangement of parts, we provide an engine in which the fuel is ejected by the compression stroke of the engine. The fuel is effectively broken up and vaporized as it is delivered by means of the air blast passage 18 and the quantity of 95 fuel may be accurately regulated by the means described.

We have illustrated and described our 100 improvements in embodiments which we consider very practical. We have not attempted to illustrate or describe certain other modifications or adaptations which we contemplate, as we believe the disclosure made will enable those skilled in the art to which our invention relates to embody or adapt our improvements as may be desired.

Having thus described our invention, what we claim as new and desire to secure 110 by Letters Patent is:

1. In an internal combustion engine, the combination with a cylinder provided with an air inlet valve, an exhaust valve and a coacting piston, of a cylindrical charging chamber member having spirally disposed ports delivering to said cylinder, a cylindrical charging valve arranged within said charging chamber member to control said ports, said charging valve being subject to the pressure within said charging chamber and within said cylinder whereby it is actuated to control said ports, a charging air passage from said cylinder to said charging chamber, a fuel nozzle operatively associated with said air charging passage whereby a charge of fuel is vaporized and delivered to said charging chamber on the compression stroke of the piston, said charging valve being closed by the pressure of said charging stroke, a plunger-like charging chamber 120

adjusting member arranged in said charging chamber member in an opposed relation to said charging valve, an ignition member for said charging chamber carried by said 5 adjusting member and aligned with the charging nozzle whereby the charge is ignited in said charging chamber and pressure generated to open said charging valve and eject the charge into the cylinder, and 10 an adjustable stop for regulating the opening of said charging valve.

2. In an internal combustion engine, the combination with a cylinder provided with an air inlet valve, an exhaust valve and a 15 coacting piston, of a cylindrical charging chamber member having ports delivering to said cylinder, a cylindrical charging valve arranged within said charging chamber member to control said ports, said charging 20 valve being subject to the pressure within said charging chamber and within said cylinder whereby it is actuated to control said ports, a charging air passage from said cylinder to said charging chamber, a fuel 25 nozzle operatively associated with said air charging passage whereby a charge of fuel is vaporized and delivered to said charging chamber on the compression stroke of the piston, said charging valve being closed by 30 the pressure of said charging stroke, a plunger-like charging chamber adjusting member arranged in said charging chamber member in an opposed relation to said charging valve, and an ignition member for 35 said charging chamber carried by said adjusting member and aligned with the charging nozzle whereby the charge is ignited in said charging chamber and pressure generated to open said charging valve and eject 40 the charge into the cylinder.

3. In an internal combustion engine, the combination with a cylinder provided with an air inlet valve an exhaust valve and a co-acting piston, of a cylindrical charging 45 chamber member having ports delivering to said cylinder, a cylindrical charging valve arranged within said charging chamber member to control said ports, said charging valve being subject to the pressure within 50 said charging chamber and within said cylinder whereby it is actuated to control said ports, a charging air passage from said cylinder to said charging chamber, a fuel nozzle operatively associated with said air 55 charging passage whereby a charge of fuel is vaporized and delivered to said charging chamber on the compression stroke of the piston, said charging valve being closed by the pressure of said charging stroke, an 60 auxiliary air inlet passage for said charging chamber, said charging air passage and auxiliary air passage being provided with check valves, a plunger-like charging chamber adjusting member arranged in said 65 charging chamber member in an opposed

relation to said charging valve, and an ignition member for said charging chamber carried by said adjusting member and aligned with the charging nozzle whereby the charge is ignited in said charging chamber and 70 pressure generated to open said charging valve and eject the charge into the cylinder.

4. In an internal combustion engine, the combination with a cylinder provided with a piston, an air inlet valve and an exhaust 75 valve, of a charging chamber having spirally disposed ports delivering to said cylinder, a charging valve controlling said ports said charging valve being subject to the pressure within said charging chamber and within 80 said cylinder whereby it is actuated to control said ports, a charging air passage leading from said cylinder to said charging chamber, a fuel feed means operatively associated with said air charging passage 85 whereby a charge of fuel is delivered to said charging chamber on the compression stroke of the piston, said charging valve being closed by the pressure of said charging stroke, an auxiliary air inlet passage for said 90 charging chamber, said charging air passage and auxiliary air passage being provided with check valves, a plunger-like charging chamber adjusting member, means whereby the charge is ignited in said 95 charging chamber and pressure generated to open said charging valve and eject the charge into the cylinder, and means for regulating the opening of said charging valve. 100

5. In an internal combustion engine, the combination with a cylinder provided with a piston, an air inlet valve and an exhaust valve, of a charging chamber having spirally disposed ports delivering to said cylinder, a charging valve controlling said ports, said charging valve being subject to the pressure within said charging chamber and within 105 said cylinder whereby it is actuated to control said ports, a charging air passage leading from said cylinder to said charging chamber, a fuel feed means operatively associated with said air charging passage whereby a charge of fuel is delivered to said 110 charging chamber on the compression stroke of the piston, said charging valve being closed by the pressure of said charging stroke, a plunger-like charging chamber adjusting member, means whereby the charge is ignited in said 115 charging chamber and pressure generated to open said charging valve and eject the charge into the cylinder, and means for regulating the opening of said charging valve. 120

6. In an internal combustion engine, the 125 combination with a cylinder provided with a piston, an air inlet valve and an exhaust valve, of a charging chamber having spirally disposed ports delivering to said cylinder, a charging valve controlling said ports, said 130

charging valve being subject to the pressure within said charging chamber and within said cylinder whereby it is actuated to control said ports, a charging air passage leading from said cylinder to said charging chamber, a fuel feed means operatively associated with said air charging passage whereby a charge of fuel is delivered to said charging chamber on the compression stroke 10 of the piston, said charging valve being closed by the pressure of said charging stroke, means whereby the charge is ignited in said charging chamber and pressure generated to open said charging valve and eject 15 the charge into the cylinder, and means for regulating the opening of said charging valve.

7. In an internal combustion engine comprising a cylinder, a piston, an air inlet and 20 exhaust valve, the combination of a charging chamber having a plurality of ports delivering to said cylinder, a valve controlling said ports, a fuel feed means comprising a passage connecting said cylinder to said 25 charging chamber whereby on the compression stroke of the piston, a charge of fuel is delivered to said charging chamber, said valve being subject to the cylinder pressures whereby it is closed on the compression 30 stroke, an ignition means for said charging chamber, said charging valve being opened by the pressure within the charging chamber, and means for controlling the opening of said charging valve, all coacting for the 35 purpose specified.

8. In an internal combustion engine, the combination of a cylinder, a charging chamber delivering to said cylinder, a valve controlling the delivery connection, a fuel feed 40 means comprising a passage from said cylinder to said charging chamber whereby on the compression stroke of the engine a charge of fuel is delivered to said charging chamber, said valve being subject to the cylinder pressures whereby it is closed on the compression 45 stroke of the engine, an auxiliary air inlet for said charging chamber, means for varying the volume of said charging chamber, means for igniting the charge in said charging chamber whereby the charging valve is opened and the charge ejected into said cylinder, and means for controlling the opening of said charging valve, all coacting for the purpose specified.

55 9. In an internal combustion engine, the combination of a cylinder, a charging chamber delivering to said cylinder, a valve controlling the delivery connection, a fuel feed means comprising a passage from said cylinder to said charging chamber whereby on the compression stroke of the engine a charge of fuel is delivered to said charging chamber, said valve being subject to the cylinder pressures whereby it is closed on the 60 compression stroke of the engine, means for varying the volume of said charging chamber, and means for igniting the charge in said charging chamber.

varying the volume of said charging chamber, means for igniting the charge in said charging chamber whereby the charging valve is opened and the charge ejected into said cylinder, and means for controlling the opening of said charging valve, all coacting for the purpose specified.

10. In an internal combustion engine, the combination of a cylinder, a charging chamber delivering to said cylinder, a valve controlling the delivery connection, a fuel feed means comprising a passage from said cylinder to said charging chamber whereby on the compression stroke of the engine a charge of fuel is delivered to said charging chamber, said valve being subject to the cylinder pressures whereby it is closed on the compression stroke of the engine, an auxiliary air inlet for said charging chamber, and means for igniting the charge in said charging chamber whereby the charging valve is opened and the charge ejected into said cylinder, all coacting for the purpose specified.

11. In an internal combustion engine, the combination of a cylinder, a charging chamber delivering to said cylinder, a valve controlling the delivery connection, a fuel feed means comprising a passage from said cylinder to said charging chamber whereby on the compression stroke of the engine a charge of fuel is delivered to said charging chamber, said valve being subject to the cylinder pressures whereby it is closed on the compression stroke of the engine, and means for igniting the charge in said charging chamber whereby the charging valve is opened and the charge ejected into said cylinder, all coacting for the purpose specified.

12. In an internal combustion engine, the combination of a cylinder, of a charging chamber delivering to said cylinder, a charging valve controlling the delivery to said cylinder, a passage connecting said cylinder to said charging chamber, a fuel delivery means operatively associated with said passage whereby a charge of fuel is delivered to said charging chamber on the compression stroke of the engine, an auxiliary air inlet for said charging chamber, means for varying the volume of said charging chamber, and means for igniting the charge in said charging chamber.

13. In an internal combustion engine, the combination with a cylinder, of a charging chamber delivering to said cylinder, a charging valve controlling the delivery to said cylinder, a passage connecting said cylinder to said charging chamber, a fuel delivery means operatively associated with said passage whereby a charge of fuel is delivered to said charging chamber on the compression stroke of the engine, means for varying the volume of said charging chamber, and means for igniting the charge in said charging chamber.

14. In an internal combustion engine, the combination with a cylinder, of a charging chamber delivering to said cylinder, a charging valve controlling the delivery to said cylinder, a passage connecting said cylinder to said charging chamber, a fuel delivery means operatively associated with said passage whereby a charge of fuel is delivered to said charging chamber on the compression stroke of the engine, means for varying the volume of said charging chamber, a control

means for said charging valve, and means for igniting the charge in said charging chamber.

In witness whereof, we have hereunto set our hands and seals in the presence of two witnesses.
